UNITED STATES PATENT OFFICE.

LEON S. HOWE, OF NEW YORK, N. Y.

METALLIC SHIPPING-PACKAGE.

1,004,028.

Specification of Letters Patent. Patented Sept. 26, 1911.

Application filed July 1, 1911. Serial No. 636,471.

To all whom it may concern:

Be it known that I, LEON S. HOWE, a citizen of the United States, and a resident of the borough of Manhattan, county, city, and State, of New York, have invented certain new and useful Improvements in Metallic Shipping-Packages, set forth in the following specification.

This invention relates to a new package as an article of manufacture.

It is customary to reinforce packed wooden boxes by nailing a strip of strap-iron around each of the two ends of the box. When the strap-iron is available merely in bulk in the form of a continuous strip, the shipping clerk is required first to pull out an indefinite length of the strap-iron; he must then measure off from the end of the strip a length sufficient to encircle the end of the box; he must then cut off the measured length; he must then again measure off the same length of strip for the other end of the box; and he must then cut off this second measured length.

An object of the present invention is practically to halve the labor formerly required for accomplishing the above result.

To that end this invention contemplates in its embodiment a novel package of strap-iron, in which two surface-overlying strips of strap-iron are combined, as two sandwiched, helical strips, into a compact pan-cake-like structure so that the outer strip, when marked or indented at regular distances along its length, may serve as a lineal measurer for itself and also for the combined underlying strip of strap-iron.

In strapping a box from a package according to this invention, the shipping clerk simultaneously unwinds the required length of strap-iron from each of the two combined helical strips and simultaneously cuts off the same measured length from the end of each of the two strips, one to be used on one end of the box and the other to be used on the other end of the box.

The invention will be clear from the following specification, which is directed particularly to the illustrative embodiment of the invention shown in the accompanying drawings, which form a part of this application, in which like characters designate corresponding parts and in which,—

Figure 1 is a perspective view showing the new package complete and in use; Fig. 2 is a fractional elevation drawn to an en-

larged scale and partly in section, showing the finished article; and Fig. 3 is a diagrammatic view in elevation showing the winding of the sandwiched helices.

A wooden disk shaped hub 1 is centrally perforated and serves as a pivot bearing for rotatably supporting the completed structure. The two ends 2 and 3 of the strips of strap-iron 4 and 5 are shown biting into the notch 6 of the hub 1. With the strips 4 and 5 maintained always with their surfaces overlying as indicated in Fig. 3, the hub 1 is forcibly rotated so as to wind up and combine the helix 7 with the helix 8 so that the turns of the helix 7 alternate with the turns of the helix 8, the helix 8 having each turn overlying a turn of the helix 7 and so that the two helical strips 4 and 5 are sandwiched and combined to form a pan-cake-like structure 9. The strip 4 of the helix 8, having each of its turns overlying a turn of the helix 7, is shown provided with lineal markers 10 which are spaced uniformly along the length of the strip 4 to mark off units of length such as feet or a unit denoting the complete end circumference of a box, such as the box 11 to be strapped.

Upon the completion of the structure 9, a binder should be provided. In the embodiment illustrated, a strap-iron yoke 12 is shown diametrically embracing both flat sides of the pan-cake-like structure 9 so as to provide means spanning the edges of the helical strips and at its ends 13 and 14 binding the same in compact array. A tubular rivet 15 is shown securing the yoke 12 by passing through the perforation 16 of the hub 1.

To employ the article illustrated, the two strips 4 and 5 together are grasped by the hand and are pulled out a length indicated by a mark 10 provided on the outer strip. The shipping clerk then needs merely to cut off the ends of the two strips in a manner shown in Fig. 1 to obtain, by the one operation, two strips of strap-iron, each of the proper length for binding each of the two ends of the box 11.

What is claimed and what is desired to be secured by United States Letters Patent is:

A strap-iron package comprising a set of a combined plurality of surface-overlying, sandwiched, helical strips of strap-iron, all of the same width and forming a compact

pan-cake-like structure and so that a single exposed strip of a set may serve as a lineal measurer for all the strips of said set; a central pivot-bearing for rotatably supporting said structure; and means spanning the edges of said helical strips for binding the same in compact array.

In witness whereof, I have signed my name to this specification, in the presence of two subscribing witnesses.

LEON S. HOWE.
